(57) **CLAIM**

The ornamental design for a notebook computer, as shown and described.

DESCRIPTION

FIGS. 1-7 show the notebook computer in a first position of use where the sub-display protrudes from the main display. FIG. 1 is a perspective view of the notebook computer; FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIGS. 8-14 show the notebook computer in a second position of use where the sub-display is inserted into the main display.

FIG. 8 is a perspective view of the notebook computer;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown in the figures that are immediately adjacent to the shaded areas and define unshaded regions represent the bounds of the claim. The bounds of the left, right, top, and bottom sides of the large display screen extend beyond the solid line showing of the edges, wherein only the broken line edges form no part of the claimed design. All other broken lines, including the features within broken line boundaries, are directed to environment. The broken lines form no part of the claimed design.
